UNITED STATES PATENT OFFICE.

HANS KANOFFSKY, OF MILWAUKEE, WISCONSIN.

NONBREAKABLE BUTTON.

Application filed February 10, 1921. Serial No. 443,887.

To all whom it may concern:

Be it known that I, HANS KANOFFSKY, a citizen of the United States, and resident of Milwaukee, in the county of Milwaukee and State of Wisconsin, have invented certain new and useful Improvements in Nonbreakable Buttons; and I do hereby declare that the following is a full, clear, and exact description thereof.

10 My invention refers to buttons for garments and the like, and it has for its object to provide as a new article of manufacture a simple, economical and effective button, which is composed of a compound such as 15 rubber or the like, whereby the button is uniformly flexible.

The primary object of the button is to prevent breakage in washing or passing through wringers or the like, also to prevent 20 the cutting of threads which attach the buttons to the garment, and to prevent slippage of the button.

Another object is to mold or form the button from material colored throughout, to 25 meet the various trade requirements. A further object is to provide a button wherein wire material or other inserts or reinforcement is avoided, it being understood that the button, when composed of rubber compound, 30 is vulcanized at such temperature that the heat from flatirons, boiling water or acids can be effectually resisted.

With the above and other minor objects in view, the invention consists in certain 35 peculiarities of construction, combination of parts as are hereinafter set forth with reference to the accompanying drawings and subsequently claimed.

In the drawings:

40 Figure 1 represents a plan view of a standard type of button made in accordance with my invention, and

Figure 2 is a cross section of the same, the section being indicated by line 2-2 of 45 Figure 1.

Referring by characters to the drawing, 1 represents the body of a circular button having four apertures 2 therein of ordinary type for the purpose of attaching the button to a garment in the usual manner, the 50 apertures being formed in a counter-sunk circular recess upon one face of the button, while the opposite face of said button is

convexed slightly, as shown at 3, the convex face and the flat face, being connected by a rounded edge 4. The button is molded, pressed, or cut preferably from a compound of rubber that is vulcanized sufficiently to resist high temperatures, but is at the same time quite flexible or pliable. Obviously, 55 the thread which passes through the holes for retaining the button to the clothing will not cut, due to its contact with the resilient material. In other words, the thread is cushioned in its contact with the button 60 walls.

Obviously, I may vary the shape of the button indefinitely and also the number of attaching holes, without departing from the spirit of my invention.

In practice, it has been found, by actual test, that the button composed of rubber compound and vulcanized sufficient to resist high temperatures will last indefinitely, 70 under ordinary usage and conditions. Furthermore, there is no breakage of these soft buttons when a garment is ironed or pressed by the ordinary type of sad-iron or an electric heated iron. It has also been found that the button will not deteriorate when subject to boiling water or acids.

It is to be noted that the button is thickened adjacent its central portion to provide the requisite strength and that it gradually tapers towards its edge to provide the additional flexibility adjacent the edge. Further the central portion of the button may be recessed so as to provide a depression to prevent the securing threads from protruding above the upper plane of the button. This thickened central portion will provide the necessary body to resist severe stresses even when the button is subjected to the heat of ironing.

To sum the matter up briefly, the button is primarily a soft flexible or pliable new article of manufacture, non-breakable, and the life of the button is therefore insured, even though it is subjected to the severe usage to which the ordinary type 100 is put. It is also within the scope of my invention to mold the button from any plastic material, which is capable of flexibility or pliability, and furthermore, buttons of this character can be colored to suit the 105 trade requirements, the coloring matter be-

ing added to the compound in process of manufacture so that it strikes through the entire body of the article.

I claim:

5 A new article of manufacture comprising a button composed of homogeneous, permanently flexible, non-absorbent material, and

having a flexible edge and having apertures adjacent its central portion.

In testimony that I claim the foregoing ¹⁰
I have hereunto set my hand at Milwaukee,
in the county of Milwaukee and State of
Wisconsin.

HANS KANOFFSKY.
